UNITED STATES PATENT OFFICE.

ANDREW EPPLER, OF LYNN, MASSACHUSETTS, ASSIGNOR TO UNITED SHOE MACHINERY COMPANY, OF PATERSON, NEW JERSEY, A CORPORATION OF NEW JERSEY.

SHOE-SEWING MACHINE.

1,092,568.

Specification of Letters Patent.

Patented Apr. 7, 1914.

Original application filed August 8, 1908, Serial No. 447,542. Divided and this application filed March 11, 1912. Serial No. 633,083.

To all whom it may concern:

Be it known that I, ANDREW EPPLER, a citizen of the United States, residing at Lynn, in the county of Essex and State of Massachusetts, have invented certain Improvements in Shoe-Sewing Machines, of which the following description, in connection with the accompanying drawings, is a specification, like reference characters on 10 the drawings indicating like parts in the several figures.

The present invention relates to inseam shoe sewing machines, and is intended primarily as an improvement on inseam shoe 15 sewing machines of that class which form a chain-stitch and which are provided with a curved hook needle entering the shoe from the outside, and with a stitch-setting take-up operating to pull the last-formed loop 20 tightly around the shank of the needle while the needle is in the work. An example of this class of machine is the well-known Goodyear welt and turn shoe sewing machine, the construction and mode of operation 25 of which is disclosed with substantial accuracy in the patent to French and Meyer, No. 412,704. As will be obvious to those skilled in the art, however, certain features 30 of the present invention are equally applicable to other types of inseam shoe sewing machines, and it is to be understood that except as defined in the claims the several features of the present invention are not limited to use in any particular type of inseam shoe 35 sewing machine.

Machines of the type disclosed in the patent to French and Meyer above referred to are provided with a thread arm to form a loop of thread on the supply side of the work 40 between the work and the needle so as to permit the thread to be drawn through the work by the needle without rendering through the hook of the needle. These machines are also provided with a looper to 45 lay the thread in the hook of the needle, and with an auxiliary spring-pressed take-up, the function of which is to take up the slack thread during the falling movement of the main take-up and keep the thread under 50 sufficient tension to enable the needle to be looped with certainty. In these machines, as heretofore constructed, the auxiliary and

main take-ups having been so arranged and operated that the auxiliary take-up continues to exert a strain on the thread after 55 the needle is looped and during the first portion of the retracting stroke of the needle while the thread arm is giving up thread. As a result, the auxiliary take-up often exerts sufficient strain on the thread to pull 60 back thread from the thread finger and thereby shorten the loop so that the needle is not supplied with a sufficient length of thread between the needle and the work 65 during its retracting movement and the thread is caused to reeve to an objectionable extent through the hook of the needle.

One of the objects of the present invention is to prevent this shortening of the loop drawn out by the thread finger, and with 70 this object in view a feature of the invention contemplates arranging and operating the main and auxiliary take-ups in such manner that the auxiliary take-up is prevented from exerting a strain on the thread during the 75 movement of the thread arm in giving up thread to the needle and is thereby prevented from stealing thread from the thread arm. In the preferred construction for securing this result, which construction is the simplest 80 and most efficient which the applicant has yet devised, a fixed stop is provided for limiting the movement of the auxiliary take-up under the tension of its spring, and this stop is so arranged with relation to the path 85 of movement and time of operation of the main take-up that it stops the movement of the auxiliary take-up at such time as to relieve the thread from the tension exerted thereby during the thread delivering movement of the thread arm. To enable the movement of the auxiliary take-up under the force of its spring to be stopped at the desired time during the operation of the machine under different adjustments and 95 upon stock of different character and quality, the means for stopping the auxiliary take-up preferably has provision for adjustment.

In machines of the type disclosed in the 100 patent to French and Meyer above referred to, the needle at the end of its retracting movement exerts a pull upon the thread to shorten the preceding loop, which loop was

pulled tight around the shank of the needle by the take-up when the needle was in the work. The necessity for this pull by the needle at the end of its retracting stroke is 5 due to the fact that the shank of the needle is larger than the two strands of thread making up the loop which is pulled through the work by the needle. It is desirable that the pull exerted by the needle be sufficient 10 to shorten and tighten the preceding loop with certainty regardless of the character of the material being operated upon.

The pull which can be exerted upon the thread by the needle to produce the best results varies with different kinds of stock, and an object of the present invention is to provide simple and efficient means whereby the needle pull can be varied as may be desired. To this end a feature of the present 15 invention contemplates the provision of means whereby the relative movement of the main and auxiliary take-ups can be adjusted to vary the amount of thread given up by the take-up to the needle during the 20 retracting stroke of the needle. This feature of the invention contemplates the provision of any suitable means whereby the relative movement of the take-up and auxiliary take-up can be adjusted to vary the amount 25 of thread given up by the take-up to the needle during its retracting stroke. The simplest and most efficient way of securing this result which the applicant has devised 30 consists in the provision of an adjustable stop for limiting the rising movement of the auxiliary take-up. By adjusting this stop the position of the auxiliary take-up with relation to the main take-up is changed, and thereby the amount of slack thread 35 given up by the take-up to the needle is varied, although, of course, the amount of thread pulled from the supply by the take-up during its rising movement remains the same, since the take-up must always pull 40 from the supply the amount of thread consumed in forming the preceding stitch. In this connection it is to be noted that the adjustment of the stop which limits the falling movements of the auxiliary take-up permits 45 adjustment of the falling movement to prevent the auxiliary take-up from stealing thread from the thread finger under any adjustment of the stop for limiting the rising movement of the auxiliary take-up.

50 In the accompanying drawing illustrating the preferred form of the invention, the figure is a view in side elevation of a welt sewing machine embodying the invention.

The machine illustrated in the drawings 55 is of the same general type as that illustrated in the French and Meyer patent 412,704. The thread handling devices of the machine comprises a curved hook needle, a looper, a thread arm, and a tension device, 60 all of which have the same construction and

arrangement and are operated by the same mechanism as the corresponding parts of the shoe sewing machine disclosed in applicant's pending application, Ser. No. 447,542, filed August 8, 1908, of which the present application is a division. These parts are therefore only briefly described in this application.

In the drawing 1 indicates the oscillatory curved hook needle carried by the needle segment 2 arranged to oscillate about the stud 3, 4 the looper, 5 the thread arm, 6 the welt guide, 7 the back rest and 8 the tension device.

The main take-up of the machine is of usual construction and consists of a thread truck 9 mounted upon the forward end of a cam actuated lever 10. The auxiliary take-up consists of a thread truck 11 mounted upon the forward end of a pivoted arm 12. The arm 12 of the auxiliary take-up is pressed upon by a spring actuated plunger 13. This plunger is mounted in a vertical guideway in the frame of the machine, and its upper end is acted upon by a coiled spring 14 seated in a recess in the machine frame between the upper end of the plunger 13 and an adjustable abutment screw 15. The auxiliary take-up is thus spring-pressed, its upward movements being resisted by the tension of the spring 14. The thread, indicated at 16, after passing over the tension wheel at the rear of the machine, passes over a guide truck 17, then under the truck 11 of the auxiliary take-up, and then over the truck 9 of the main take-up. The arrangement of these trucks is such that during the rising of the main take-up, the auxiliary take-up is moved upward, and during the falling movements of the main take-up the auxiliary take-up is allowed to fall and maintain a tension on the thread determined by the strength of the spring 14 and the relative positions of the three trucks. The main take-up falls during the thread pulling movement of the thread arm, during the looping movements of the looper, and during the retracting stroke of the needle. To prevent the auxiliary take-up from stealing thread from the thread arm during its loop delivery or forward stroke, and while the needle is making the first part of its retracting stroke, a stop 18 is provided to limit the falling movement of the auxiliary take-up, which stop is engaged by an adjustable abutment screw 19 mounted in the lever 12 of the auxiliary take-up. The stop 18 and abutment screw 19 are so arranged with relation to the falling movement of the main take-up and the thread delivering stroke 125 of the thread arm, that the falling movement of the auxiliary take-up is stopped before the thread arm begins its thread delivering stroke. During the first portion of the falling movement of the main take-up,

130

therefore, and while the needle is being looped, the auxiliary take-up exerts a tension on the thread, but this tension is removed at such time as to prevent any liability of the stealing of thread from the thread arm.

The main take-up of the machine illustrated in the drawing acts in the same manner as that of the machine of the French and Meyer Patent No. 412,704 to pull off thread from the supply during its upward stroke and to give up this thread to the needle during its falling stroke to such an extent that the needle will exert a pull on the preceding loop of the seam and shorten this loop. To secure a variation of the pull exerted by the needle on the thread in shortening the preceding loop, the machine illustrated in the drawings is provided with an adjustable stop for limiting the rising movement of the auxiliary take-up, this stop being indicated at 20 and consisting of an adjustable screw threaded abutment screw mounted in the frame of the machine. An adjustment of the stop 20 will vary the amount of thread extending from the looper around the main and auxiliary take-ups to the truck 17, and consequently will vary the amount of thread given up by the take-up during the falling movement to the needle. An adjustment of the stop 20 will obviously vary the time in the operation of the machine at which the abutment 19 of the auxiliary take-up will hit the stop 18 during the falling movement of the auxiliary take-up. The abutment 19 is, therefore, made adjustable so that the falling movement of the auxiliary take-up can be stopped at the desired time in the operation of the machine under any adjustment of the stop 20. This adjustment of the abutment 19 of the auxiliary take-up also permits an adjustment for variation in the operation of the stitch forming devices occasioned by differences in the kind of stock operated upon.

It is to be understood that the invention is not limited to the details of construction and operation of the illustrated embodiment but the invention may be embodied in other forms within the scope of the claims.

The nature and object of the invention having been explained and a machine em-

bodying the preferred form thereof having been specifically described, what is claimed is:

1. A chain stitch shoe sewing machine having, in combination, a hook needle, a looper, a thread arm, a take-up, a spring-pressed auxiliary take-up, and means having provision for adjustment for stopping the movement of the auxiliary take-up under the force of its spring to prevent the auxiliary take-up from stealing thread from the thread arm.

2. A chain stitch shoe sewing machine having, in combination, a hook needle, a looper, a take-up, an auxiliary take-up, and means for adjusting the amount of thread given up by the take-up to the needle to vary the pull exerted upon the thread by the needle in tightening the preceding loop.

3. A chain stitch shoe sewing machine having, in combination, a hook needle, a looper, a take-up, a rising and falling spring-pressed auxiliary take-up, and a stop to limit the rising movement of the auxiliary take-up having provision for adjustment to vary the amount of thread given up by the take-up to the needle and thereby vary the pull exerted upon the thread by the needle in tightening the preceding loop.

4. A chain stitch shoe sewing machine having, in combination, a hook needle, a looper, a take-up, a rising and falling spring-pressed auxiliary take-up, and means having provision for adjustment to vary both the rising and falling movement of the auxiliary take-up.

5. A chain stitch shoe sewing machine having, in combination, a hook needle, a looper, a take-up, a rising and falling spring-pressed auxiliary take-up and means for adjusting the relative movement of the take-up and auxiliary take-up to vary the amount of thread given up by the take-up to the needle and thereby vary the pull exerted upon the thread by the needle in tightening the preceding loop.

In testimony whereof I have signed my name to this specification in the presence of two subscribing witnesses.

ANDREW EPPLER.
